ABSTRACT OF THE DISCLOSURE

A twist latch having a twistable latch mounted on a base in which the latch is urged into seating engagement on the base in either locked or unlocked position by the engagement of cam fingers in the base with a flared or tapered cam surface of a shaft on the latch.

SUMMARY OF INVENTION

Twist latches are old and well known Leggo Pat. No. 1,206,866 discloses a twistable latch seated by a spring. Phillips Pat. No. 1,474,208 in 1923 discloses a similar spring-loaded latch. Poupitch Pat. No. 2,601,213 in 1952 shows a still further development in which cam surfaces overcome a spring washer. Seckerson Pat. No. 3,335,471 in 1967 shows a locking pin for seating the twist latch.

None of these devices is especially suitable for being fabricated of plastic materials.

The present twist latch is especially devised for fabrication of plastic materials and takes advantage of the inherent resiliency of the plastic material to co-operate with a cam surface to seat the twist latch in locked or unlocked condition.

A very inexpensive and durable twist latch is thereby provided which may be fabricated very cheaply and may be easily attached to other surfaces or bodies.

The foregoing objects and advantages, as well as other objects and advantages, may be attained by the device shown by way of illustration in the drawings in which:

DRAWINGS

FIG. 1 is a side elevational view of the latch portion of the twist latch;

FIG. 2 is a top plan view of the base of the twist latch;

FIG. 3 is a vertical sectional view taken on the line 3—3 in FIG. 2 looking in the direction of the arrows;

FIG. 4 is an end elevational view of the latch shown in FIG. 1;

FIG. 5 is a view in perspective of the twist latch assembly in latching position;

FIG. 6 is a view in perspective of the twist latch assembly with the latch in unlocked position;

FIG. 7 is a partially sectioned view of the assembly with the latch in unlocked position; and

FIG. 8 is a view of the co-operative fasteners for attaching the twist latch assembly to an object.

DETAILED DESCRIPTION

Referring now to the drawings in detail, the twist latch therein shown provides a handle 10 with one side relatively larger than the other and flat to enable it to be easily seized and twisted. The twist latch 11 has a shaft 12 depending therefrom. The upper portion 14 of the shaft is shown to be tapered, but this is merely a design feature. The lower portion 15 of the shaft has a flared portion defining a cam surface. Immediately beyond the lower portion 15, there is a head 13, which is generally in the shape of an inverted dome. The head 13 has a pair of ears 16 on opposite sides. The bottom of the handle 10 of the twist latch 11 has a longitudinal rib 17 which intersects with the shaft 12 and extends on both sides of it. The upper portion of the shaft 14 and the lower

2

portion 15 of the shaft define an annular seat 29 or constriction at the narrowest portion of the shaft.

The twist latch assemblage has a base 21. The base is elongated. It is noted that the handle 10 is also elongated so that when the handle is disposed transverse to the base, it extends beyond the base. The base 21 may be slightly larger in its cross-sectional area progressively from top to bottom. This top enlargement 22 is generally flat and is provided with a latitudinal channel 25 defining a seat for the twist latch 11 in locked position, and a longitudinal channel 24 (optional) defining a seat for the twist latch 11 in unlocked position. A flange 30 defines a seat for a fastener as will be hereinafter referred to. The flange 30 has a pair of slots 31. There is a top central aperture 23 on the top of the base 21. This aperture, as will be seen from FIG. 2, is generally circular with opposite enlargements dimensioned sufficiently great to permit the insertion of the latch and to particularly pass the ears 16. Surrounding the top central aperture 23 and depending downwardly therefrom on opposite sides thereof, there are a pair of resilient fingers 26. These fingers 26 are sufficiently long so that their lower end will be in engagement with the cam surface 15 slightly below the constriction or narrow point 29 when the twist latch 11 is inserted fully into the aperture 23, and the rib 17 is seated either in the latitudinal channel 25 or the longitudinal channel 24. The fingers 26 assert pressure on the cam surface 15, thereby normally urging the rib 17 into seated engagement with either of the channels 24, 25 when in registration with them, or when at an intermediate position, to bear firmly on the top of the base 21. It will be seen that when the twist latch 11 is turned to disengage the rib 17 from either of the channels 24, 25, the shaft 12 will tend to move out of the base 21. This will tend to cause the resilient fingers 26 to ride up the flared lower surface 15. The fingers will be deformed outwardly and by reason of their resiliency, will exert pressure tending to restore the twist latch 11 to its normal position with the rib 17 seated in either of the channels 24, 25, when it is positioned in registration with the channels 24, 25. Thus, the latch operates through the combination of spring pressure exerted by the resilient fingers and by the cam action of the resilient fingers upon the lower portion 15 of the shaft 12. The shaft 12 is thereby constantly urged into the base 21 with the effect of seating the rib 17 in locked or unlocked position in either of the channels 24, 25. The ears 16, 16 will prevent extreme force from withdrawing the latch 11 from the base 21 when the latch is in any position except the unlocked position. In the unlocked position, extra force and deflection of the fingers 26 to disengage them from a shoulder 36 will permit the withdrawal of the latch 11 from the base 21.

At the top of the head 13, at the point of intersection with the flared lower surface 15, there is defined a flat shoulder 36.

In operation, with the handle 10 in locked position (FIG. 5), excessive axial force exerted on the handle 10 may tend to withdraw the handle 10 from the base 21, except for the fact that the fingers 26 will ride down the surface 15 until the ears 16 engage the fingers 26, thereby preventing the separation of the handle 10 and the base 21.

On the other hand, in unlocked position, the excessive axial force exerted on the handle 10 will cause the fingers 26 to ride up the surface 15. Since the ears 16 may intrude between the fingers 26, the withdrawal is in this position prevented by the fingers 26 riding down the flared lower surface 15 into seating engagement with the shoulder 36, thereby preventing the separation of the handle 10 and the base when the device is in unlocked position.

While I have referred to the rib 17 being on the handle 10 and the channels 24, 25 being on the base, it is to be understood that the position of these parts may be interchanged. The rib 17 and the channels 24, 25 need not be as long as shown, but may be made very short as long as they engage each other.

In order to apply the twist latch assemblage to a body, a generally rectangular retainer 32 is provided dimensioned to fit over and around the base 21, with tabs 33 fitable into the slots 31. A retainer plate 34 is also provided with notches 35 into which the tab 33 may be fitted and bent over under the plate 34, thereby to secure the latch assemblage affirmatively to any body or sheet intruded between the base 30 and the plate 34.

The foregoing description is merely intended to illustrate an embodiment of the invention. The component parts have been shown and described. They each may have substitutes which may perform a substantially similar function; such substitutes may be known as proper substitutes for the said components and may have actually been known or invented before the present invention; these substitutes are contemplated as being within the scope of the appended claims, although they are not specifically catalogued herein.

What is claimed:

1. A twist latch comprising:
  - (a) a hollow base,
  - (b) an elongated handle twisted in registration with, or transverse to, the base,
  - (c) a rib on the handle adjacent to the base,
  - (d) a transverse channel on the base positioned to seat the rib when the handle and the base are disposed transverse with respect to each other,
  - (e) a shaft on the handle extending through an aperture into the base,
  - (f) a flared portion on the shaft defining a cam surface,
  - (g) a resilient finger on the base at the inside thereof, defining a cam, engaging the cam surface of the shaft, and normally urging the shaft into the base to seat the rib on the bottom of the handle, in the transverse channel.

2. The device according to claim 1, and a second re-

silient finger on the base at the inside thereof, defining a cam, engaging the opposite side of the cam surface of the shaft, and normally urging the shaft, in co-operation with the other resilient finger, into the base to seat the rib on the bottom of the handle, in the transverse channel.

5. The device according to claim 2 and the resilient fingers depending inwardly of the base from the edge of the aperture therein, coaxial with the shaft.

10 6. The device according to claim 1, and

- (a) a flange on the outside of the base,
- (b) slots in the flange,
- (c) a retainer seated on the flange,
- (d) detents on the retainer extending through the slots,
- (e) a notched plate,
- (f) the detents deformed around the plate through the notches.

15 7. The device according to claim 2, and

- (a) a head on the shaft defining a shoulder,
- (b) the shoulder in abutment with the resilient fingers to prevent the withdrawal of the shaft from the base when the device is unlocked.

20 8. The device according to claim 2, and

- (a) a head on the shaft defining a shoulder,
- (b) the shoulder in abutment with the resilient fingers to prevent the withdrawal of the shaft from the base.

25 9. The device according to claim 1, and a longitudinal channel on the base positioned to seat the rib when the handle and the base are in registration in unlocked position.

30 10. The device according to claim 5, and ears on the head in general vertical registration with the plane of the handle, the ears defining detents engageable with the fingers when the handle is disposed in locked position, whereby the handle cannot be axially withdrawn from the base.
